UNITED STATES PATENT OFFICE.

RICHARD G. HOOPER, OF DELAWARE, OHIO.

GAME-TABLE.

1,221,181.

Specification of Letters Patent.

Patented Apr. 3, 1917.

Application filed July 31, 1916. Serial No. 112,323.

To all whom it may concern:

Be it known that I, RICHARD G. HOOPER, a citizen of the United States, residing at Delaware, in the county of Delaware and State of Ohio, have invented new and useful Improvements in Game-Tables, of which the following is a specification.

This invention relates to a table for the playing of two games, namely, table golf and hazard.

With the above and other objects in view this invention resides in the novel features of construction, formation, combinations and arrangements of parts to be hereinafter more fully described, claimed, and illustrated by the accompanying drawing in which:—

Figure 1 is a perspective view of my table adapted for use in the playing of table golf and hazard,

Fig. 2 is a fragmentary detail perspective view of one end of one of the bars, illustrating the application of the rubber cushion thereto, and,

Fig. 3 is an enlarged cross-sectional view through the disk, illustrating the application of a similar rubber cushion thereto.

Referring to the accompanying drawing by similar characters of reference throughout the letter A designates in general my hexagonal table upon which may be played the two games table golf and hazard, through the medium of the customary cues and balls in present use upon the well-known type of pool tables so familiar to those interested in such games and in every day use throughout the country.

To play the first game that of table golf each player has a ball. The play starts by shooting the ball designated by the letter B with the cue designated by the letter C, from the rectangular space also designated by the letter D at one edge of the table to the hole indicated by the numeral 1. The ball must be gotten into this hole. If this is accomplished in one shot, the player sets the ball at the edge of said hole 1 any where within one and a half inches from said hole, and tries for the hole indicated by the numeral 2 and repeats at each hole consecutively. When the player first shooting fails to get his ball into the hole aimed for, his opponent beginning at the starting point with his own ball, tries for the hole indicated by the numeral 1 following the process of play as given above.

The game is made more intricate by reason of the facts that a series of bars indicated in general by the numeral 7, a bunker 8, a disk 9, and woods 9' protruding upwardly from the surface of the table a sufficient distance and suitably secured thereto, all of said objects being placed in such a position that it is necessary to use the cushions 10, which are made of rubber, as on the customary billiard tables now in every day use. To reach the holes in most cases direct shots for said holes are not possible and the fact that a player at any time for a shot, instead of shooting his ball for the desired hole, may, with his ball, knock his opponent's ball, to place said opponent at a greater disadvantage for his, the opponent's next shot, also the fact that of the pond indicated by the numeral 11, which forfeits one hole for the player whose ball drops into it, this is if a player is trying for the hole indicated by the numeral 4 and his ball falls into said pond he will on his next shot have to shoot from the edge of said pond for the hole indicated by the numeral 3. The player who places his ball in the hole indicated by the numeral 6, first, is the winner of said game.

In the second game, that of hazard, only one ball is used as a cue ball, the same ball being used by all the players irrespective of the number in the game and each player has a ball, known as the playing ball. All the playing balls are placed near the center of the table in a space to be designated and the player beginning the game shoots the cue ball from the rectangular space at the edge of said table, at the balls in the center of the same in an attempt to get his playing ball into the hole indicated by the numeral 1. If he succeeds in this he then places his playing ball on the edge of said hole 1, within one and one-half inches of the edge of said hole, he then tries with the cue ball to shoot his playing ball into the hole indicated by the numeral 2 and so on to each hole consecutively. A player at any time may drive his opponent's playing ball away from the position it may hold in order to gain an advantage for himself or to put his opponent at a disadvantage, and not loose his shot thereby.

When the player first shooting fails to get his playing ball into the hole for which he is aiming his opponent shoots the cue ball from the position such cue ball may occupy

2
on said table, as left by the first player, at his playing ball, wherever it may be located as left by the first player, attempting to drive his ball into the hole indicated by the 5 numeral 1 and to each hole consecutively, as above-described.

Either the cue ball or a playing ball dropping into the pond forfeits one hole to the player as previously described in the game 10 of table golf. The player first placing his ball in the hole indicated by the numeral 6 is declared winner of the game same as in that of table golf as before described.

It may be further stated that the disk 9 is 15 of a diameter equal to the length of the bars indicated in general by the numeral 7 and the height of said disk being equal to the height of the side of said table from the playing surface thereof to the top surface 20 of the cushions 10, this feature being clearly illustrated in Fig. 1 of the accompanying drawing.

It may be still further stated that the bars indicated in general by the numeral 7 as 25 illustrated by the drawing are made of steel, the cross bars 12 being round in cross-section and of any suitable diameter, covered with rubber or any suitable material as indicated by the numeral 13, while the supporting end 30 posts 14 of said cross bars 12 are square in cross-section and also of any suitable thickness as clearly illustrated by Fig. 2 of the accompanying drawing. These end posts are also provided with a rubber cushion 15 35 of suitable design which is secured to the upper end of each of said posts and envelop the same on three sides thereof as clearly illustrated by the above-mentioned views. This cushion 15 is in close proximity to the 40 upper cross bar 12 and in alinement with the cushions 10 of the table A proper.

It is now thought that the above description together with the accompanying drawing sufficiently sets forth the method to be 45 adopted for successfully playing these two games, to enable those familiar with this art to readily understand the arrangement of objects used in connection with this table

and the necessary moves to make in order to play either of said games to advantage. 50

It should also be understood, however, in this connection that various minor changes in the details of construction may be resorted to within the scope of the appended claims, without departing from or sacrificing 55 any of the advantages of this invention.

From the foregoing disclosure taken in connection with the accompanying drawing it will be manifest that I have provided a game table for use in connection with the 60 two games, namely, table golf and hazard, which will fulfil all of the necessary requirements of such a table.

Having thus fully described this invention, what I claim, and desire to protect by 65 Letters Patent, is:—

1. In combination with a game table, having a cushion surrounding its periphery in close proximity with the surface of said table, a series of bars mounted upon the surface of said table, a pond formed in the surface of said table, a disk mounted upon the surface of said table, a series of apertures formed in the surface of said table, a woods arranged upon the surface of said table and 70 a bunker mounted upon the surface of said table as and for the purpose set forth.

2. In combination with a table, having an elastic cushion surrounding its periphery in close proximity with the surface of said 80 table, a series of bars mounted upon the surface of said table and covered with elastic material, a plurality of posts supporting each of said series of bars, an elastic cushion substantially secured to each of said 85 posts, a pond formed in the surface of said table, a disk mounted upon the surface of said table, a series of apertures formed in the surface of said table, a woods arranged upon the surface of said table and a bunker mounted upon the surface of said table as 90 and for the purpose set forth.

RICHARD G. HOOPER.
